Primary Examiner — Jeffrey D Asch*Assistant Examiner* — Rebekah A Caruso(57) **CLAIM**

The ornamental design for a data cable, as shown and described.

DESCRIPTION

FIG. 1 is a front elevational view of a data cable showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The data cable may be used on an electronic device such as unmanned aerial vehicles (UAVs), remote controls, mobile phones, computers, tablet computers for data transformation, signal transmission, power transmission and so on. The data cable is shown with a symbolic break in its length. The appearance of any portion of the article between the break lines forms no part of the claimed design.
